FUSE

John H. Hanson and William E. Underwood,
Chicago, Ill.

Application March 14, 1933, Serial No. 660,750

8 Claims. (Cl. 200—131)

This invention relates to certain novel improvements in a fuse.

We are aware of the fact that there are many types of renewable cartridge fuses known. In general these prior art fuses comprise a single cartridge or shell of fibrous or other insulating shell, a renewable fusible strip arranged in the shell, metal reenforcing rings in the ends of the shell, and metal caps closing the ends of the shell and rings and contacting with the fuse strip. Experience and experimentation with renewable fuses of this type have, however, taught us that they are unsatisfactory and unsafe, for a number of reasons, among which are: When the fuse strip in a fuse of this type "blows" or melts the electric arc formed during the melting of the fuse strip fuses the metal closure and contact caps at the ends of the shell to the reenforcing rings or bushings, making it very difficult, and often impossible, to remove the closure caps to replace the fuse strip, and thus necessitating that the cartridge be discarded. Moreover, the electric arc and the heat formed when a fuse strip melts pulverizes the metal fuse strip. As a series of fuse strips are successively used up and fused in the same shell a film of metal gradually accumulates on the inner surface of the shell, from end to end of the same, and this film contacting with the metal rings, caps, or closure members usually arranged at the ends of the shell forms a conductor that destroys or negatives the circuit and fire protection afforded by the fuse strip in the shell. This is because of the fact that even if the fuse strip melts, due to a short or other disturbance in the circuit, the circuit is still very apt to be kept closed by the said metallic film formed on the inner side of the shell, as aforementioned, by the successive fusing of metal fuse strips which may be from time to time replaced in the same shell. For these and other reasons single shell renewal cartridge fuses have in general been refused approval by the fire insurance underwriters and for this reason have never come into general use.

Objects of our invention, therefore are: to provide a renewable cartridge fuse which overcomes the aforementioned and other defects in the prior art renewable cartridge fuses; which is positive and reliable in use; which will meet with the approval of the fire insurance underwriters; and to provide a double shell cartridge fuse having an inner replaceable refill cartridge in which the fuse strip is disposed, and which refill cartridge may be taken out of the outer shell and discarded, after each successive fuse strip melts, and

replaced by a new refill cartridge, thereby preventing the accumulation of a metallic film on the inner surface of the outer shell.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a perspective view of a preferred form of the new fuse;

Fig. 2 is a longitudinal sectional view of the new fuse on line 2—2 in Fig. 1;

Fig. 3 is a longitudinal sectional view of the new fuse on line 3—3 in Fig. 2;

Fig. 4 is a transverse sectional view on line 4—4 in Fig. 3;

Fig. 5 is a perspective detail view of a preferred form of the new fuse showing the parts disassembled; and

Fig. 6 is a longitudinal sectional view of a slightly modified form of the new fuse.

The new fuse is indicated generally at 10 in the drawing and comprises a double shell consisting of an outer insulating or non-conductive shell 11 and an inner insulating or non-conductive shell 12, both of which shells may be made of fiber or other suitable non-conductive material.

The fusible strip 13 is arranged in the inner 85 and replaceable shell 12 and has end portions 15 extended out through the open ends of the inner shell 12. These end portions 15 are bent over bullet or wedge-shaped closure members 14. One of these wedge-shaped closure members is arranged in and acts as a closure for each open end of the inner shell 12. These closure members 14 may be made of metal, such as brass, for example, or other material but they are preferably made of a non-conductive or insulating material, a preferred form of which is porcelain.

The end portions 15 of the fuse strip 13 are electrically connected to contact members 17 by means of electrically conductive closure members in the form 90 of metal caps 16. These caps 16 are threaded into the metal contact members 17 which are in the form of bushings that are threaded onto the end portions of the outer shell 11. In the form of the fuse shown in Figs. 1 to 5, inclusive, both ends of the outer shell are closed by closure cap 16 threaded into the contact bushings 17; while in the modified form of the fuse shown in Fig. 6 one end of the outer shell 11 is closed by a contact bushing 18 that is similar to the contact

100

105

110

115

bushings 17 but has an integral portion 19 closing one end of the outer shell; the portion 19 taking the place of one of the caps 16. Otherwise the two forms of the new fuse are the same.

5 Each of the closure members 14 has a flat side or face extending longitudinally thereof so as to provide an air vent in each end of the inner shell 12 for the escape of the heated gases and vapors through the ends of the inner shell when the 10 fuse strip 13 melts.

The refill cartridge, consisting of the inner shell 12, the fuse strip 13, and the closure members 14, may be manufactured as a separate unit or article of manufacture and sold as a refill for 15 the outer shell 11; the refill cartridge being made by assembling the fuse strip 13 and the closure members 14, as shown, with the end portions 15 of the fuse strip angled over the outer ends of the closure members 14. The refill cartridge 12—13—14 may then be inserted into the outer shell 20 or cartridge 11, by removing one of the closure members or caps 16, whereupon the said cap 16 may be replaced by threading the same into its bushing or contact member 17 thereby forcing 25 both angled end portions 15 of the fuse against the metal closure caps 16. In this manner a positive, efficient electrical connection is effected between the fuse strips 13 and the contact rings or bushings 17 by way of the closure caps 16.

30 When the fuse strip 13 is melted or "blows", one of the closure caps 16 may be removed and the inner cartridge 12—13—14 may then be removed from the outer shell 11. The used inner cartridge 12—13—14 may then be discarded and a new refill 35 cartridge 12—13—14 be placed in the outer shell 11, and the whole assembled for use as shown; or, a new fuse strip 13 may be placed in the shell 12 and the closure members 14 replaced to form a new refill cartridge, if desired. However, destruction of the used inner shell 12 and 40 substitution of a new refill cartridge, or at least a new inner shell 12, is desired since this does away with the danger incident to repeated use of the inner shell 12, namely, that a film of metal 45 may accumulate on the inner surface of the inner shell 12, if the same is used repeatedly, and thus negative, in the aforementioned manner, the protection afforded by the fuse strip 13.

The closure members 14, being made of non-conductive material, the arc and heat incident to the fusing of the strip 13 do not fuse these closure members 14 to the metal closure caps 16, nor to the contact rings 17, and hence the inner cartridge 12—13—14 may be readily removed 55 from the outer shell and replaced; thus obviating a difficulty experienced in the use of the prior art single shell cartridge fuses, namely, that the arc and heat incident to the melting of the fuse commonly caused the closure members at the ends of the single shell to fuse to the contact rings so 60 that the shell could not be opened to replace the fuse strip.

We have shown a preferred structure for effecting an efficient electrical connection between the 65 end portions 15 of the fuse strip 13 and the contact members 17 but we are aware that this arrangement may be varied and we contemplate such variations in the appended claims; the invention being clearly indicated in the claims as 70 residing broadly in the refill cartridge 12—13—14 and in the combination or assembly of the refill cartridge 12—13—14 with the outer shell and contact members; rather than in any one detail of the structure shown.

75 Having thus described our invention what we

claim as new and desire to protect by Letters Patent is:

1. In a renewable fuse, a tubular member, a fuse strip positioned in said tubular member and having its ends projecting beyond the ends of the tubular member, a plug pressed into each end of the tubular member and having a flange, said fuse strip being pinched between the plugs and the inner wall of said tubular member and between the ends of the tubular member and said flanges, each plug being provided with a flat side, a second tubular member enclosing the first-mentioned tubular member, and end caps having threaded connections with the second tubular member for closing the ends of the same. 80

tween the fuse strip and the ferrules, said plugs applying endwise pressure to the insert.

6. A fuse comprising a tubular shell having a contact ferrule arranged about each of its ends, each ferrule being provided with a threaded opening; an insert comprising an inner tube having a fuse strip extending therethrough and plugs pressed into its open ends, the ends of the fuse strip being bent over the exposed ends of said plugs; said insert being of smaller proportions than said tubular shell and arranged within the latter, and a threaded closure plug screwed into each of the threaded openings in the ferrules for establishing electrical contact between the fuse strip and the ferrules, said closure plugs applying endwise pressure to the insert, at least one of said first-named plugs having a cut-away portion to provide a vent opening communicating with the interior of the inner tube, at least one of said closure plugs having an opening co-operating with said cut-away portion to provide a vent communicating with the atmosphere.

7. A fuse comprising a tubular shell having a contact member connected with one end and arranged to provide an abutment projecting over one open end of the shell, a contact member connected with the opposite end of the tubular shell and having an opening, a rigid insert having a fuse strip associated therewith, the ends of the fuse strip projecting beyond the ends of the insert, said insert being of non-conductive material and having end abutments, the ends of the fuse strip being bent to lie adjacent said end abutments, one of the bent ends of the fuse strip bearing against the abutment part of said

first-named contact member, and a plug of conductive material adjustably positioned within the opening in the second-named contact member and in electrical contact with the opposite bent end of the fuse strip, said plug being arranged to apply endwise pressure to the insert.

8. A fuse comprising a tubular shell having a contact ferrule arranged about each of its ends, one of said ferrules providing an abutment, the other of said ferrules being provided with a threaded opening, an insert comprising an inner tube having a fuse strip extending therethrough with its ends projecting beyond the inner tube, a plug structure positioned within the inner tube to provide abutting surfaces, said inner tube and said plug structure being made of non-conducting material, the ends of said fuse strip being bent to lie over the said abutting surfaces, said inner tube being smaller in diameter than said threaded opening for insertion therethrough, one of the bent ends of said fuse strip bearing against the abutment part of said one ferrule, to establish electrical contact between the ferrule and the fuse strip, and a threaded member of conductive material screwed into said threaded opening in the other of said ferrules, to establish electrical contact between the other bent end of the fuse strip and the last-mentioned ferrule, said threaded member being arranged for applying endwise pressure to the insert, to pinch bent ends of the fuse strip between said plug structure and the threaded member and said abutment.
